1 Claim. (Cl. 137—567)

The present invention concerns a vacuum apparatus with a receiver, for example an electronmicroscope or an electron diffraction apparatus, to which is connected a pumping system consisting of a diffusion pump and a forevacuum pump, and which possesses a lock chamber for the introduction or removal of objects.

With such equipment it is frequently very disturbing if the forevacuum pump must be kept running during the operation; often the noise or the mechanical vibration caused by the running pump or the stray magnetic field produced by the motor of the pump are disturbing while observing the electronmicroscope picture. It is therefore proved to be generally useful to provide for a so-called forevacuum reservoir in such pump systems, that is a reservoir which helps to replace the forepump of the diffusion pump so long as a given maximum pressure is not exceeded in it. This maximum pressure corresponds to the maximum permissible pressure on the exhaust side of the diffusion pump (forepressure breakdown) at which it can still carry out its pump function directly; if this pressure is exceeded the pump action breaks down. The period, during which the forepump can remain cut off longest, thus the maximum time at ones disposal for undisturbed work with an electronmicroscope varies with, the size of the so-called forevacuum reservoir, the forepressure breakdown of the diffusion pump, the volume of the lock chamber, the gas evolution and the leak tightness of the reservoir as well as with the interval between each two introductions. Should the time span for undisturbed work be required to be large, an unwieldy large vacuum reservoir would become necessary, especially so, if, as with electronmicroscopes, electron diffraction apparatus and the like, new objects must be introduced into the apparatus through a lock chamber, where each time a large amount of air also penetrates. The object of the invention is to eliminate these disadvantages.

According to the invention it is proposed that in a vacuum system with a receiver, a diffusion pump for exhausting the receiver, a forevacuum pump and lock chamber for introducing and removing objects from the receiver, to provide a first and second vacuum reservoir for said system. One vacuum reservoir into which the diffusion pump can exhaust and the other reservoir provided for the lock chamber.

Only limited space is available in vacuum equipment for the installation of forevacuum reservoirs. Utilization of the available space, according to the invention, for two separate forevacuum reservoirs, permits one to achieve, in a surprising way, a significantly longer, undisturbed, operating time with the pump shut off. It is possible in this way to accumulate in a given total volume for both forevacuum reservoirs about a 50 fold or more greater amount of gas, before the forevacuum pump must again be operated, than is the case for only one forevacuum reservoir of the same total volume.

An embodiment of the invention will be explained by an example and the accompanying sketch.

In the sketch, 1 represents the receiver, 2 a diffusion pump connected to the receiver through a valve 3 (in the case of the example) 4 represents a vapor jet pump

2

installed before the diffusion pump (this may be omitted if desired), and 5 a first forevacuum reservoir, which, as was mentioned, has the task of receiving the gases expelled from the diffusion or vapor jet pumps, while the forevacuum pump is shut off. The insertion of a vapor jet pump gives the advantage, that the maximum permissible pressure in the reservoir 5 corresponds to the higher forepressure breakdown of a vapor jet pump which is greater in comparison to that of a diffusion pump. The parts mentioned to this point are connected with each other through pipes 6, 7 and 8, as is evident from the sketch, while the forevacuum reservoir 5 is connected with the forevacuum pump 9 through the valve 10 and through these must be brought to a reduced pressure from time to time, which pressure will be chosen to be so low (<0.1 torr), that it can be taken as practically equal to zero for all subsequent considerations. In a known manner, a so-called bypass line, for the purpose of evacuating the receiver, bypasses the diffusion pump and connects the receiver 1 through a valve 11 with the forepump 9 as well as a valve 12 for the inlet of atmospheric air into the receiver (flooding).

A lock chamber 13 for the introduction and removal of objects is added to the equipment. This is represented schematically in the sketch, since the design details of the lock as well as the holding and moving arrangements for the objects or preparations for the electronmicroscope are not of interest for the description of the invention. The connections to the lock chamber are shown according to their function, on the one side with the receiver, on the other side with the atmosphere from which the system is isolatable by the valves 14 and 15. In order to bring an object into receiver, it is placed in the chamber 13 through the valve 15 and after closing valve 15 and opening valve 14 the insertion of the object into the receiver can be worked out in different ways by means of suitable known transport mechanisms. The removal occurs in reverse order. Often the main point is to place the lock chamber in communication with the receiver, whereby the object can remain in the chamber 13, for example, in preparations for the electronmicroscope. In the operation of the described equipment by procedures and methods known up to now, the gas present in the lock chamber would be removed either after opening the valve 14 through the pump 2 or through the bypass line. Equipments are also known, in which the lock chamber is provided with its own evacuation line. So far the equipment described up to now has shown no novelty and corresponds to the known state of the art.

However, according to the invention a second separated forevacuum reservoir 16 is provided for the lock and is connected with it through the pipe 17, isolatable through the valve 18, and connected to the suction side of the forevacuum pump through the pipe 19. For operation of the equipment the two forevacuum reservoirs 5 and 16 are first brought to a reduced pressure by the forepump which is necessary for the operation of the diffusion or vapor jet pumps. Thereupon the valves 10, 11 and 20 are closed. The pumps 2 and 4 can remain in operation and the receiver further evacuated or held at a fixed pressure, until through the gas accumulation; (introduced through the outgassing of the assembled parts and inner walls and the objects brought in, or through air, which is introduced through leaks or through the lock) the pressure in 5 is increased beyond the above mentioned maximum pressure. Then the forevacuum pump must again be put in operation.

The optimal distribution of the available volume for the two forevacuum reservoirs together can be easily determined according to the known formulas of the theory of gases, since it depends, as has been mentioned,

on the forepressure breakdown of the diffusion or vapor jet pumps put into the system, on the gas accumulation from the recipient and from the lock chamber and on the volume of the lock chamber. Further, the number of lockings per second, the interval between each two lockings as well as the necessary duration of undisturbed readiness for operation must be taken into consideration for each individual case.

storage time span in the first and second forevacuum reservoirs, measured in torr liters and $P_1(V_1+V_2)$ states the amount of gas that can be stored, if V_1 and V_2 together form only a single forevacuum reservoir. The factor is a measure of the technical step forward produced by the invention.

The following table gives the data for a few examples of the carrying out of the invention.

V_1+V_2 (Liter)	V_1 (Liter)	P_1 (Torr)	V_2 (Torr)	P_2 (Torr)	Storable amt. of gas (Torr Liters)	μ
30	30	10	Not according to the invention		300	
	8		22	100	2,280	7.6
20	20	0.3	Not according to the invention		6	
	5		15	20	301.5	50
70	70	0.5	Not according to the invention		35	
	10		60	80	4,805	137
100	100	1.0	Not according to the invention		100	
	20		80	100	8,020	80
50	50	0.4	Not according to the invention		20	
	10		40	60	2,400	120
10	10	0.2	Not according to the invention		2	
	2		8	40	320	160

The following considerations are of interest in connection with the present invention.

The possible total volume and the forepressure breakdown of the diffusion or vapor jet pump are given. The maximum permissible pressure in the vacuum reservoir for the lock chamber is determined according to the amount of gas that may be expected in the receiver which is connected to the diffusion or vapor jet pump; this factor itself depends in addition on the pump construction and also on the kind of working fluid used, and on the proportion of the lock chamber volume to the receiver volume. It must be guaranteed that on sudden connection to the lock chamber the rising pressure in the receiver never exceeds the value that the diffusion pump will accept. This will be determined by connecting the second vacuum reservoir with the lock chamber for the purpose of roughing it down and the corresponding magnitude will be ascertained. Following these considerations and with the usually available data for forepressure breakdown, the volume of the receiver as well as the maximum available space for both of the forevacuum reservoirs one arrives most easily at a 50 fold increase in the total storable amount of gas and corresponding to a 50 fold lengthening of the undisturbed working time with the forepump shut off.

In accordance with the formula for the factor μ which is easily derivable from the theory, the total storable amount of gas in the gas of the invention is greater than for an equipment with only one forevacuum reservoir;

$$\mu = \frac{P_1 V_1 + P_2 V_2}{P_1 (V_1 + V_2)}$$

where P_1 and V_1 are respectively the maximum pressure and the volume of the first forevacuum reservoir and P_2 and V_2 signify the similar quantities corresponding to the second forevacuum reservoir. $P_1 V_1$ and $P_2 V_2$ are respectively the contained gas amounts at the end of the

The technical improvement produced by the invention depends on the fact that the gas (air) coming out of the lock chamber will be taken up for the greater part in its own forevacuum reservoir and thus the forevacuum reservoir for the diffusion and vapor jet pumps respectively is not loaded up and in which only a proportionally lower pressure is permitted to prevail. The sudden evacuation of small containers through connecting them to other evacuated containers is already known and not the object of the present invention, although, in equipment according to the invention, the advantage of evacuating the lock chamber becomes important.

An especially advantageous solution of the assigned task of the invention arises if the outgassing of the receiver itself and the objects existing within it are small, and the greater part of the gas inflow arises from the operation of the lock. The invention has advantages for other applications. If for example, in the course of electronmicroscopic preparations, the gas falling on photographic plates and films in an electronmicroscope consists predominantly of condensable vapors such as water vapor and these vapors are trapped in a cold trap or an absorption trap arranged in the suction line before the forevacuum reservoir of the diffusion or vapor jet pumps, for example, the oil baffle of the diffusion pump 2 below the valve 3 can be improved to, at the same time act in a known way as a water vapor condenser, so that the forevacuum reservoir 5 is charged only with permanent gases.

We claim:

Vacuum apparatus having a receiver to which a diffusion pump and forevacuum pump means are operatively connected, a lock chamber connected to said receiver and adapted for the introduction into and removal of objects from said receiver, a first vacuum reservoir adapted to be evacuated by said forevacuum pump means operatively connected to said diffusion pump whereby said diffusion pump may exhaust into said first vacuum reser-

voir while said forevacuum pump means is temporarily shut off, and a second vacuum reservoir operatively connected to said forevacuum pump means and adapted to be connected directly to said lock chamber, whereby said lock chamber may be evacuated into said second vacuum reservoir.
